UNITED STATES PATENT OFFICE.

RALPH W. WILEY, OF SAN FRANCISCO, CALIFORNIA.

TRAFFIC SIGNAL.

Application filed April 21, 1921. Serial No. 463,103.

To all whom it may concern:

Be it known that I, RALPH W. WILEY, a citizen of the United States, and resident of the city and county of San Francisco, State of California, have invented new and useful Improvements in Traffic Signals, of which the following is a specification.

The principal object of my invention is to secure an efficient and reliable traffic signal.

My device enables vehicle operators approaching a cross street to at once observe the condition of traffic thereon and enables the traffic officer in charge of the crossing to signal such operators to secure uniformity of traffic movement by both a sound and a visible signal.

Other objects will appear from the drawings and specifications which follow:

By referring to the accompanying drawings my invention will be made clear.

Fig. 1 illustrates a front view of my traffic signal as assembled on a suitable support and indicating one style of casing and supporting column and with the word "Stop" in exposed view.

Fig. 2 is similar to Fig. 1 and at 90° thereto.

Fig. 3 is a cross section in plan of Fig. 4 on the line III—III thereof.

Fig. 4 is an enlarged front view of the interior parts of Fig. 2, except that portions of the casing and signal member have been removed to better display the interior construction.

Fig. 5 is an enlarged detail of certain of the parts of Fig. 4, which cause the operation of the signal member.

Fig. 6 is a fragmentary view similar to Fig. 5 and at right angles thereto.

Fig. 7 is a plan section on the line VII—VII of Fig. 5.

Fig. 8 is a view of the guide bars and certain of the parts of Figs. 5, 6, and 7.

Figs. 9 and 10 are elevation and plan views of certain of the upper parts of Fig. 4 and which parts form certain of the circuit connections.

Fig. 11 is a detail cross section of the latch member shown in full in Figs. 12, 15 and 16.

Fig. 12 shows the interlocking mechanism and shutter by which the signal may

be closed from view by remote control when not in use, with the magnet bracket 55 and support rod 3 turned at right angles to their true position for illustrative purpose. Fig. 13 is a front view of the lower portion of Fig. 12 in the direction of the arrow XIII.

Fig. 14 is a plan section view of certain of the latch members for the interlocking mechanism and is taken on the line XIV—XIV of Fig. 12.

Figs. 15, 16 and 17 show the interlocking 65 mechanism and latch of Fig. 11 in their several positions.

Fig. 18 shows in plan bell striking mechanism mounted in the lower part of the signal of Fig. 4 and is a section taken 70 on the line XVIII—XVIII thereof.

Fig. 19 is a section of Fig. 18 on the line XIX—XIX and at right angles thereto.

Fig. 20 is a fragmentary elevation of the gong striking latches of Figs. 18 and 19.

Fig. 21 is a wiring diagram, showing diagrammatically the circuit connections.

Figs. 22 and 23 show my signal in use on street crossings.

Throughout the figures similar numerals 80 refer to identical parts.

Referring to Figs. 4, 5 and 6, a solenoid is indicated by the numeral 1 having in co-operation therewith a vertical moveable plunger 2. The solenoid is attached by 85 suitable fastening means to the standard 3 anchored at the top and bottom of the frame or signal casing at 4 and 5 respectively. Carried upon the said standard is the lateral axial member 6 which forms 90 a guide for a suitable slot milled in extension of the plunger 2 so that the plunger 2 is free to travel up and down within the solenoid 1 over the stationary axle 6 at the lower end and bearing 7 at the upper end. 95

In Fig. 6 the plunger is shown in full lines in its lower or released position and in dotted lines as at 8 in its retracted position when the solenoid has been energized. Carried upon the plunger 2 is a horizontal 100 pivot 11 from which are supported on each side of the plunger the link members 9 and 10. These links are pivoted at 12 to the plates 13, 14, 15 and 16 which are in line with each other and which are cross-connected by bolts 150—151 and the shank 105

of the ball member 17 and are rotatable upon the axle 6. By referring to Fig. 6 the plates are shown in full with the ball 17 in the extreme position to the right; 5 and by the dotted lines 18 in an intermediate position and by dotted lines 19 in the extreme opposite position; and during the travel from 13 to 19 the ball member has traveled from the full line position 17 to the 10 dotted position 20 and the link 9 has traveled first to the intermediate position 21 when the plate 13 is in the dotted position 18 and then to the dotted position 22 when the plunger has returned to the full line 15 position 2. The ball member 17 is clamped between plates 23 and 24 (see Fig. 8) adapted to travel upon the guide rods 25 and 26 so that as the ball member travels from the 20 position 17 to the position 20 of Fig. 7 the guide bars are moved laterally from the full line positions 25 and 26 to the corresponding dotted positions and said movement will take place in one direction or the other whenever the solenoid 1 actuates the plunger 2 up and down and throws the plates. 25 The rods 25 and 26 are mounted integrally with the base plate 27 and the top plate 28 (see Fig. 4) and are adapted to rotate the frame work 29 which is adapted to 30 receive the signal plates 30 and 31, 32 and 33, respectively forming a signal drum (see Figs. 3 and 4). The plates 13, 14, 15 and 35 16, bound together as a unitary structure are mounted rigidly upon the axle 6 which is at right angles to the movement of the plunger, and have a limited movement from the full line position as 13 in Fig. 6, to the dotted line position 19. Whenever the plunger is raised sufficiently to enable the 40 ball shaft 161 to swing thereunder, the links 9 and 10, which normally stand horizontal to the left or the right of pivot 11, depending upon whether the parts occupy the full line position or the dotted position, 45 form the operative connection between the swinging plates and when the plunger is raised, the said plates swing about the axle 6 from the full line position as 13 on the left, past the neutral point when the plunger is retracted to its greatest height and 50 due to the inertia swings to the right, that is to the dotted position 19 as the plunger falls.

This movement causes the ball 17 to move 55 from the right to the left, that is from position 17 to position 20, and that compels the oscillating movement of the drum 28 with its signal plates about the vertical axis 3. The link 9 is pivoted between the 60 plates 13 and 14 and the link 10 between plates 15 and 16. A second cycle of movement of the plunger causes a reverse movement of the plates.

Plates 13 and 16 are held in spaced relation by the bolts 151 and 150 and plates

14 and 15 are held spaced respectively from 13 and 16 by the ball shaft 161 on the one end and at the other end by the pivotal connection with the links 9 and 10 in the conventional way.

70

It will now be seen that upon the actuation of the solenoid the signal plates 30 and 32 which are exposed in the direction of the arrows 34 and 35, respectively, will be rotated out of position when the solenoid operates throwing the frame 29 in the direction of the arrow 36 and will be obscured behind the outer casing at 37 and 38 respectively, and at such time the signal plates 31 and 33 will have been operated into exposed position visible at 34 and 35 respectively. For night illumination the lamp 39 properly supported in a position behind the transparent signal plates, which are preferably made of glass, will illuminate any lettering thereon in the well known way.

75

When the signal is not being used it is necessary to close the openings observable at 34 and 35 and this I accomplish by the shutter 40 and 41, and said shutter 40 and 41 rotates in a clearance space between the rotatable plates of the drum as 32, 30 and the outer casing or frame 37, 38. The operation of this shutter is effected through a 80 separate circuit and by the following mechanism.

85

Referring to Figs. 4 and 11 to 17 inclusive, the magnet or solenoid 50 is rigidly supported from the standard 3 and has pivoted opposite to its core the armature 51 carrying an arm and roller wheel 52, the latter adapted to actuate the vertical rod 53 which latter is aligned through stationary plates as 54, 55. Carried upon the top plate 28 is the spring latch 56 having a friction engaging means 57 adapted to hold the latch in either its lower position 58 or its upper position 59. While in its lower position as shown in Figs. 11 and 12 said latch is clear of and below the plate 45 and when the signal plates are rotated to their limit position in the direction of the arrow 36 of Fig. 3 the latch 56 is in alignment with the socket 60 carried in the plate 45; the shutter member now being open so that the signal plates are exposed in the directions 34 and 35 of Fig. 3. If now the magnet 50 be energized the armature 51 will be attracted, the arm and roller 52 raised, which will cause the raising of the rod 53, and the forcing upward of the latch 56 until the friction piece 57 engages the lock groove 59 and the hook member 61 will at the same time be raised clear from the bolt socket 60 as described below. If now the solenoid 1 be actuated the plate 28 will rotate opposite to the direction of the arrow 36 of Fig. 3 and the latch 56 being in coupled relation between the plates 28 and 45 will carry with it the

shutter plates 40, 41, which have been released from the hook member 61. The shutter will therefore rotate into a position such that the faces 40 and 41 will obscure the openings 34 and 35 respectively, and the signal will be out of commission until the shutter is again opened. A suitable conventional clearance opening is provided in the plate 28 as shown at 160, so that the plate 28 being a portion of the drum may oscillate without respect to the rod 61.

By referring to Figs. 14 and 15 it will be seen that when the rod 53 is raised the latch plate 62 under the action of the spring 63 will engage against a shoulder on the said rod to hold the rod in its upper position, and when the hook member 61 is raised as described below the second latch plate 64 will engage under the collar 65 retaining the said hook member temporarily in its upper position, during which time the spring 66 is under compression.

The stationary plate 55 serves to hold the spring 66 in compression to actuate the rod 61. The plate 28 is also stationary, whereas plate 45 is connected with the oscillating axis 3 and is latched by the hook rod 61 as described.

When the solenoid 1 is again actuated the shutter will be returned to its full line position (see Fig. 3) because of the latch 56 still being in engagement with the bolt socket 60 in the rotatable plate 45. At 67 in Figs. 3 and 14 I have shown a tripping member which during the return movement here described in the direction of the arrow 36 will first force the latch plate 62 from the dotted position back to the full position of Fig. 14 and will therefore release the vertical rod 53 which will now fall, and the trip 67 will thereafter strike the second latch plate 64 causing it to move into its full line position and releasing the hook member 61 which is now acting under the compression of the spring 66, and as the plates 28 and 45 arrive at their extreme position, the hook member 61 will fall into the socket 60 as indicated in Fig. 15, causing the latch 56 to be depressed until the lock groove 58 is engaged by the friction means 57. The connection between plates 45 and 28 now being broken 45 remains at rest during subsequent action of the solenoid 1 and oscillation of the plate 28 and signal drum until such time as the magnet 50 may be again energized.

In order to prevent any damage to the apparatus and make its operation fool-proof I have shown the rod 53 jointed at 68 so that its extension end 69 under the action of the spring 70, may if it be in the up position when the plate 28 is rotated in the direction of the arrow 36 and at such time is struck by the lower end of the latch 56, will be temporarily shifted from its full line

position as to 42 Fig. 15 and upon its retraction will immediately and automatically restore itself into the full line position and be ready for actuation of the latch 56 as previously described.

I prefer to mount upon the rod 53 the lug 71 which engages under the second lug 72 which latter is mounted upon the hook member 61 so that when the rod 53 is raised by the action of the magnet 50 the rod 61 is carried with it, but when the rods are released from the latch mechanism of Fig. 14 by the trip 67 the rod 53 may first freely fall, independently of the rod 61 which latter is only later released from its plate 64. Also the rod 61 may move vertically as upon the sloped surface 73 without any actuation of the rod 53.

The action of the gong or sounding mechanism is as follows: Referring to Figs. 18, 19, 20, on the plate 27 are the latch members 80 and 81 carried in suitable sockets with compression springs and with convenient suitable stops to prevent their overtravel at 82 and 83, respectively. At 84 is a gong having hammers 85 and 86 mounted respectively upon the pivoted arms 87 and 88 which arms are held contracted by the spring 89 against a stop 74. One of these arms 87 is shown in dotted position in Fig. 18 with a hammer 85 carried on a spring arm 75 about ready to strike a blow. The arms 87 and 88 are pivoted at 90, and carry the slide members 91 and 92 respectively. These slide members upon movement of the plates about the pivot 90 describe an arc of greater radius than that within which the striking latches 80 and 81 rotate. It will now be seen that if the striking arm 87 occupies the position as shown in Fig. 20 and the base plate 27 rotates in the direction contrary to the arrow 36 the said latch 80 acting against the face of the slide plate 91 will carry the latter with it and therefore the arms 87, retracting the hammer 85 to the dotted position (see Fig. 18). As the latch 80 moving on its arc of shorter radius approaches the dotted position it will clear the surface of the slide plate 91, and hammer 85 will then strike a blow on the gong 84 through the action of the spring 89. The arm 87 and plate 91 are now restored from their dotted position to their full line position. At the same time that the latch 80 occupies its dotted position the latch 81 will have been moved to the position of the latch 80 and will therefore be in position to cause the action of the plate 92 and arm 88 and the striking by the hammer 86, when the base plate 27 is rotated in the direction of the arrow 36. When this last movement has taken place the latch 80 will ride up on the sloping surface of the plate 91 and fall into the position shown in Fig. 20 at the termination of the movement, setting the parts for

striking the gong on a movement of base plate 27 in a reverse direction.

In Figs. 9 and 10 are shown switch parts in which 104 is a brush carried on the vertical member 3 and adapted to alternately contact with the contact segments or blades 105 and 111. The brush 104 is carried on the oscillating member 3, the blades 105 and 111 being mounted on conventional insulated supports from a stationary part of the device. (See also Fig. 21.) Circuit connections are shown diagrammatically in Fig. 21. A source of electrical energy is indicated by the numeral 100 and operating keys at 101, 102 and 103. The diagram illustrates two of my signal devices connected in parallel adapted to be controlled from a single point, it being understood that any number of these signals may be operated from a single station.

In Fig. 22 I have shown four of my signals mounted at a street crossing and at Fig. 23 a single traffic signal device 130 mounted at a street crossing. In the latter instance it will be understood that the same signal is given on both sides at the same time. In other words there will be diametrically opposite to the exposed window of the signal 35 a similar window and signal plate and diametrically opposite 34 a similar signal plate, see Fig. 3. The signal member in this case being continuous around the inner periphery of the device and the shutter in this case being constructed to close or open all four of the openings at the same time.

Assuming the signal to have been out of commission with the shutter 40 and 41 closing all the openings and obscuring the signal. The latch 56 will now be engaged with the plate 45 as indicated in Fig. 16. The brush 104 will be in engagement with contact segment 105. The operator throws switch 102 contacting at 106 and closing the circuit through the lamp 39 to illuminate the signal. He then operates the double throw switch 103 to contact at 107. The current flows through the wire 108, segment 105, brush 104, wire 109, solenoid 1, wire 110, energizing the solenoid which actuates the plunger which throws the plate 28 in the direction of the arrow 36 as previously described. The signals being in parallel the same action takes place in all and the signal members as 28 and 28' will be rotated opposite the now exposed openings 34, 35, respectively, and the first signals will be displayed. The brush 104 will now have made contact with the segment 111, the solenoid circuit will have been broken when the brush 104 was disengaged from segment 105 and the current will automatically have been interrupted. To operate the signal again the double throw switch 103 is thrown to engage contact 112 which through wire 113, segments 111 and brush 104, wires 109 and

110 again energizes solenoid 1. The parts having been in full line position of Fig. 6 will upon this energization be thrown into a dotted position 19 and the plates 28, 28' will have rotated in a direction reverse to arrow 36, the circuit being automatically again interrupted when the brush 104 leaves segment 111. On the first of the above movements in the direction of 36 the trip 67 will have operated the latches 62 and 64 releasing bolt 56 from engagement with plate 45 so that the shutter is left in its open position; after which the second and any further movements, take place, the signaling being accomplished as often as may be desired by the movement of the plate 28 in one direction or the other through the operation of the double throw switch 103 to either contact 107 or 112 as may be required.

When the signal is to be closed for the day the parts are first to be set by the switch 103 contacting at 107 which causes the plate 28 to rotate into the position so that the shutter actuated parts are in the position shown in Fig. 15. The operator now depresses key 101 which actuates magnet 50 raising the rod 53 and engaging latch 56 with plate 45 and disengaging hook 61 therefrom. The double throw switch 103 is now contacted with 112 and plate 28 and shutter plate 45 rotated in the opposite direction to the arrow 36 causing the shutter plates as 40 and 41 to rotate in front of the openings 34 and 35 respectively, and closing the signal.

In utilizing my invention it will be clear that any signals as Stop or Go or any other desired characters may be placed upon the signal plates. In Fig. 1 I have indicated the word Stop as being fully exposed in one direction at the same time that the word Go is indicated in the direction at right angles thereto. Such an arrangement of signals would be suited to the use of my invention in a signal device at a street crossing as indicated at 130 in Fig. 23. Where the municipal traffic is heavy or the crossing wide I prefer to introduce four of my signal devices as indicated in Fig. 22 and in the upper part of said figure I have indicated at 120 a street car and at 121, 122, respectively, automobiles which have been held up by the setting of the signal 123. In such a position as this I prefer to expose the same signal on both faces 34 and 35; that is; the setting here shown presupposes the signal having indicated the word Stop at both faces 34 and 35. The motorman of the car 120 is relatively close to the signal in the position shown and can readily read the small figures, whereas a motorist in the position 124 would be unable to read the small lettering exposed at 35 and will therefore not be deceived thereby, but will depend upon the indications in his adjacent signal at 125. With the parts set as here

shown it is indicated that both signal plates in the signal stations 123 and 127 shall indicate the word Stop, and that both plates in each of the signals 125 and 126 shall indicate the word Go. Traffic will then be open in the horizontal direction of the figure and will be closed in the vertical direction of the figure. The street car at 120 will be able to see clearly the signal in 123 and upon a shifting of the plates 28 in the four stations 123, 125, 126, and 127 by the operation of the double throw switch 103 from contract 107 to contract 112 all four of the signal plates as 28 will rotate, reversing the respective signals, closing the traffic on the horizontal line of the figure and opening traffic on the vertical line.

Should the signal operator desire to stop all traffic as in the event of clearing a way for fire apparatus, the signals on all four corners (Fig. 22) must now be set to indicate Stop.

Referring to Fig. 21 it will be seen that when the signal plate 28 of the corner signal 123 has rotated in the direction of the arrow 36 to set the signal at, say, "Go" the signal plate 28' of the corner signal 125 will have rotated to indicate "Stop". Now in the event of fire the traffic signal at 123 must be set to indicate "Stop" without interfering with the present setting of the corner signal at 125. This is accomplished by the operator opening the switch at 135. This opens the circuit of the corner signal 125 which stands at Stop and the switch 103 is now operated so that the corner signal 123 is now operated and is thrown also to indicate Stop and all traffic is halted at the crossing:

40 I claim:

1. In a traffic signal, a casing, a drum, means mounting said drum for oscillation about a vertical axis within the casing to two signaling positions, means for moving the drum from one position to the other comprising a solenoid having a vertically reciprocating plunger, a rock shaft mounted for oscillation about a horizontal axis and having a connection with said drum, a link connecting said rock shaft and said plunger whereby a complete movement of said plunger into and out of said solenoid moves the signal from one position to the other.

2. In a traffic signal, a casing, a signal drum, means mounting said drum to oscillate within a casing, a shutter interposed between the drum and the casing and a disengageable device for connecting the shutter and the drum whereby the drum may be rotated with or independently of the shutter.

3. In a traffic signal the combination set forth in claim 2 and electromagnetic means associated with said device and adapted to actuate said device to connect or disconnect

the drum and shutter respectively.

4. In a traffic signal, a rotatable signal drum mounted on a vertical axis within a casing, means for oscillating said drum comprising a solenoid having a vertically positioned reciprocating plunger, a horizontal oscillating rock shaft and connection therefrom to said drum, an arm on said shaft and a link between said arm and said plunger whereby as the plunger makes a reciprocating movement under the action of the solenoid the rock shaft is oscillated from one side to the other, a shutter interposed between the drum and the casing and means between the shutter and the drum adapted to engage and to disengage the shutter and drum.

5. In a traffic signal the combination set forth in claim 4 and electromagnetic means constructed and adapted to actuate said device.

6. A traffic signal, comprising a casing having an opening, a drum mounted to oscillate within the casing and having thereon a plurality of signal characters which are respectively exposed through said opening when the drum is oscillated, means mounting the drum to oscillate to two positions and other means for oscillating the drum, a shutter between the drum and casing and movable to cover the said openings to obscure the drum characters, and mechanism between the drum and shutter whereby the drum and shutter are connected to move together or disconnected to allow of independent movement.

7. A traffic signal comprising the combination set forth in claim 6 and electric actuated means constructed and adapted to oscillate said other means.

8. A traffic signal comprising the combination set forth in claim 6 and electric actuated means constructed and adapted to oscillate said other means and other electric actuated means actuating said mechanism.

9. A traffic signal, comprising a casing having a plurality of openings, a drum mounted to oscillate within the casing and having thereon a plurality of signal characters which are respectively exposed through said openings when the drum is oscillated, means mounting the drum to oscillate to two positions and other means for oscillating the drum, a shutter between the drum and casing and movable to cover the said openings to obscure the drum characters, and mechanism between the drum and shutter whereby the drum and shutter are connected to move together or disconnected to allow of independent movement.

10. A traffic signal comprising the combination set forth in claim 9 and electric actuated means constructed and adapted to oscillate said other means.

11. A traffic signal, comprising a casing

having a plurality of openings, a drum mounted to oscillate within the casing and having thereon a plurality of signal characters which are respectively exposed through said openings when the drum is oscillated, means mounting the drum to oscillate to two positions and other means for oscillating the drum, a shutter between the drum and casing and movable to cover

the said openings to obscure the drum characters, and mechanism between the drum and shutter whereby the drum and shutter are connected to move together or disconnected to allow of independent movement, and electric actuated means actuating said mechanism.

RALPH W. WILEY.
